(57) **CLAIM**

The ornamental design for a swivel hanger, as shown and described.

DESCRIPTION

FIG. 1 is a perspective view of a swivel hanger, showing my new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof;

FIG. 8 is a front view of the handle component of the swivel hanger of FIG. 1 shown without the hanger component for clarity of illustration;

FIG. 9 is a top view thereof;

FIG. 10 is a bottom view thereof;

FIG. 11 is a rear view thereof;

FIG. 12 is a front view of the hanger component of the swivel hanger of FIG. 1 shown without the handle component for clarity of illustration;

FIG. 13 is a bottom view thereof;

FIG. 14 is a rear view thereof;

FIG. 15 is a top view thereof;

FIG. 16 is an exploded top front perspective view of the swivel hanger of FIG. 1;

FIG. 17 is a top front perspective view of the swivel hanger of FIG. 1;

FIG. 18 is a top front perspective view of the swivel hanger of FIG. 1 showing the handle component in an alternate position; and,

FIG. 19 is a top front perspective view of the swivel hanger of FIG. 1 showing the handle component in a second alternate position.

The broken lines and arrowheads shown in FIGS. 18 and 19 are reference symbols representing the direction of the handle component of the swivel hanger, all of which form no part of the claimed design.

1 Claim, 9 Drawing Sheets
